DESIGN FOR A BACK FOR BILLFOLD OR SIMILAR ARTICLE

Morris Marcus, New York, N. Y., assignor to Centra Leather Goods Corporation, New York,
N. Y., a corporation of New York

Application April 3, 1945, Serial No. 118,843

Term of patent 3½ years

(Cl. D87—3)

To all whom it may concern:

Be it known that I, Morris Marcus, a citizen of the United States, residing at New York city, in the county and State of New York, have invented a new, original, and ornamental Design for Back for Billfold or Similar Article, of which the following is a specification, reference being had to the accompanying drawing, forming part thereof.

The figure is a plan view of a back for billfold or similar article, showing my new design. The other side, not shown, is substantially plain.

I claim:

The ornamental design for a back for billfold or similar article, substantially as shown and described.

MORRIS MARCUS.
